(57) **CLAIM**

The ornamental design for a pneumatic carrier, as shown and described.

DESCRIPTION

FIG. 1 is a front perspective view of a pneumatic carrier in an open condition showing our new design;

FIG. 2 is another front perspective view drawn partially in fragment showing the inside of the lid on an enlarged scale;

FIG. 3 is a bottom perspective view drawn partially in fragment showing the inside surface of the top portion;

FIG. 4 is a side perspective view thereof in a closed condition; and,

FIG. 5 is a side perspective view of the side opposite that shown in FIG. 4.

The broken lines shown in FIGS. 2 and 3 illustrate the reference of these views with respect to FIG. 1 and form no part of the claimed design.
